(57) **CLAIM**

The ornamental design for novelty utensil, as shown and described.

DESCRIPTION

FIG. 1 is a side view of the novelty utensil. Both sides are mirror images and only one side is shown.

FIG. 2 is a front view of the novelty utensil.

FIG. 3 is a rear view of the novelty utensil.

FIG. 4 is a top view of the novelty utensil.

FIG. 5 is a bottom view of the novelty utensil; and,

FIG. 6 is a perspective view of the novelty utensil.

The broken lines shown in the drawings are for illustrative purposes only and form no part of the claimed design.

The novelty utensil of the present invention is characterized by ornamental features resulting in the design and style of the invention.
